No. 783,857.

PATENTED FEB. 28, 1905.

DE WITT M. COINER.
SHUTTER WORKER.
APPLICATION FILED AUG. 26, 1904.

UNITED STATES PATENT OFFICE.

DE WITT M. COINER, OF STATESVILLE, NORTH CAROLINA.

SHUTTER-WORKER.

SPECIFICATION forming part of Letters Patent No. 783,857, dated February 28, 1905.

Application filed August 25, 1904. Serial No. 222,081.

To all whom it may concern:

Be it known that I, DE WITT M. COINER, a citizen of the United States, residing at Statesville, in the county of Iredell and State of North Carolina, have made certain new and useful Improvements in Shutter-Workers, of which the following is a specification.

My invention is an improvement in shutter-workers, and has for an object to provide a novel construction whereby a sprocket-chain may be utilized for opening and closing the shutters, the shutters may be supported in such manner that they may be readily operated and may be removed from the operating or working devices at will, and by which the sprocket-chain may be tightened up whenever desired; and the invention consists in certain novel constructions and combinations of parts, as will be hereinafter described and claimed.

In the drawings, Figure 1 is a front elevation of the outer side of a pair of blinds provided with my improvements. Fig. 2 is a horizontal section on about line 2 2 of Fig. 1. Fig. 3 is an enlarged horizontal section on about line 3 3 of Fig. 1. Fig. 4 is a detail perspective view of the shutter-section. Fig. 5 is a detail sectional view of the operating-section, and Fig. 6 is a detail section on about line 6 6 of Fig. 4.

In carrying out my invention I provide a sprocket-chain A, which extends between what for convenience of reference I term the "shutter-section" B and the "operating-section" C, the former being arranged on the outer side of the sill D and the latter on the inner side of the said sill or within the room in convenient reach of the operator. The shutter-section B comprises a suitable casing having upper and lower plates B' and B², between which the sprocket-wheel E is arranged, and also provided at its ends with lugs b for the screws, by which the section B is secured to the window-sill. The plates B' and B² are provided at b' with openings forming bearings, in which journal the hub extensions e of the sprocket-wheel E, one of said hub extensions journaling in the upper plate B' and the other in the lower plate B², so the sprocket-wheel is journaled permanently in the upper

and lower plates of the section C, as will be understood from Fig. 4 of the drawings. The sprocket-wheel is provided with a central angular opening e', which extends entirely through it and receives the pintle or shaft G' 55 on the lower end of the butt G, which is secured to the shutter H near its lower end. This shaft G' may move freely in a longitudinal direction within the opening e', but is keyed in the sprocket-wheel E so it must 60 turn in connection with said wheel, so that the turning of the wheel E will turn the shaft G', and thus turn the shutter from open to closed position, and vice versa. In order to relieve the sprocket-wheel of the weight of 65 the shutter H, I support such shutter entirely from its upper hinge, leaving the lower hinge or pivot of the shutter free of all weight, so that it may be operated freely without regard to the weight of the shutter. This also permits the ready removal of the shutter whenever desired by simply lifting same when open without in any degree deranging the shutter-working devices. 70

The chain A connects the sprocket-wheel E 75 with the sprocket-wheel J, which is journaled in the upper and lower plates of the operating-section C so the turning of the wheel J will correspondingly operate the wheel E. At its upper side the wheel J is provided with a lever 80 J', having a detent-pawl J' engaging with the racks J² on the section C, so the wheel J may be held in any desired position in order to hold the shutter open, closed, or in any intermediate position. It will be noticed that the 85 pivot of the wheel J is set sufficiently away from the inner edge of the sill D to permit the lever J' to be swung back against the said sill and at an angle to the face of the sill in order to take up any shrinkage in the material. 90 The section C is also provided with lugs C', provided with slots C², elongated, as best shown in Fig. 5, so the screws C³ passing through said slots in the sill may be slackened and the section C be adjusted along the sill in order 95 to take up any slight slack in the chain A.

The construction is simple, can be easily applied to shutters in new work or in old, and will be found to operate efficiently for the desired purpose.

Having thus described my invention, what I claim as new, and desire to secure by Letters Patent, is—

1. The improvement in shutter-workers herein described, comprising in combination with the sill and the shutters the operating-section having its casing provided with bearings for the operating sprocket-wheel and with lugs for the securing-screws, said lugs having slots 5 elongated in the direction of length of the section whereby the latter may be adjusted along the sill when secured thereto, the operating-wheel journaled in said section and having an operating-lever, the shutter-section having 10 upper and lower plates provided with bearings for the sprocket-wheel, the sprocket-wheel having upper and lower hub-sections journaled in their bearings, said wheel being provided with a central angular opening for the shaft 15 of the lower butt of the shutter, the sprocket-chain connecting said sprocket-wheels, and the lower shutter-butt having a depending shaft fitting in the central opening of the sprocket 20 of the shutter-section and movable longitudinally therein, substantially as set forth.
- 25

2. A shutter-worker comprising a shutter-section having a journaled sprocket-wheel provided with a central opening for the shaft of the shutter-butt, means for turning said sprocket-wheel and the shutter-butt having a depending shaft fitting in the opening in the sprocket-wheel and keyed from turning therein and movable longitudinally in said opening, substantially as set forth. 30

3. The combination in a shutter-worker, the shutter-section having upper and lower plates provided with bearings, the sprocket-wheel arranged between said plates and having hub projections journaled in the bearings of said upper and lower plates, said sprocket-wheel 35 being provided with a central non-circular opening and the shutter-butt having a shaft movable longitudinally in the central opening of said sprocket and keyed from turning therein, substantially as set forth. 40

DE WITT M. COINER.
